UNITED STATES PATENT OFFICE.

GRACE FERN PETER, OF CHICAGO, ILLINOIS.

CLOTHES-HANGER.

1,144,058.

Specification of Letters Patent. Patented June 22, 1915.

Application filed May 2, 1913. Serial No. 765,059.

To all whom it may concern:

Be it known that I, GRACE FERN PETER, a citizen of the United States, residing at Chicago, Cook county, Illinois, have invented 5 certain new and useful Improvements in Clothes-Hangers, of which the following, taken in connection with the drawing, is a description.

My invention has for its object the production of a clothes hanger of the class 10 designed to be folded for convenience when not in use, or when traveling about from place to place.

This invention is so constructed and arranged that it may be used as a coat hanger, and is provided with means for engaging a skirt or other garment which may be suspended therefrom.

In the accompanying drawings I have 20 illustrated what I now consider the preferred form of my invention, although many of the details of construction may be changed without departing from the spirit thereof, and in these drawings—Figure 1 is 25 a longitudinal sectional view of the device showing the depending clamps secured thereto; Fig. 2 is a top plan view of the same; Fig. 3 is a bottom plan view of the hanger with the arms folded inside and Fig. 30 4 is an enlarged transverse sectional view of the end of the casing.

Referring to the drawing, a casing is formed of an upper and lower elongated plate a , a' . Between these plates at each end 35 thereof is a disk a^2 , a^3 , which provides a chamber or compartment between the plates a , a' . Upon the under side of the upper plate at one end thereof, and upon the upper side of the under plate at the opposite end 40 is a groove b , shown more clearly in Fig. 4, the purpose of which will be more clearly described later.

Pivottally secured between these two plates at the ends thereof are the arms A , A' , 45 which are turned upon the pivots b' , b^2 to extend said arms to the open position shown in Figs. 1 and 2, or to be folded inside the casing as shown in Fig. 3.

Positioned between the arm A and the 50 plate a is a spring c , shown more clearly in Fig. 4 which exerts a pressure against the arm to hold it more closely in contact with the plate a above it. The arm A is provided upon one side thereof with a slightly raised 55 surface c' , which, when the arm is turned

to open position turns into the groove b to form an engagement which prevents any accidental sidewise motion of said arm. This construction is the same at each end of the hanger, therefore a description there- 60 of for the opposite end will not be repeated.

Near the outer edge of the upper and lower plates a , a' is provided a corrugation d , d' which adds strength and rigidity to the frame. The upper plate a is provided 65 with grooves e , e' which form a guide way in which moves a sliding member E , E' . Hinged to each of these sliding members is a plate E^2 , E^3 , hinged at their opposite ends to the center plate E^4 . Secured to this center plate E^4 is a hook F . When in closed position the plates E^2 , E^3 , E^4 lie flat upon the upper plate a as shown more clearly in Fig. 2, but when the hanger is ready for use, the hook is pulled upwardly, raising 70 the plates E^2 , E^3 , E^4 to the position shown in dotted lines in Fig. 1, which forms a raised collar support for the coat or other garment to be hung upon the device.

Hinged to the plate a' and adapted to 80 depend therefrom in open position are engaging clamps G , G' , to which may be secured a skirt or other garment. When the hanger is closed, the two clamps are turned into the openings g , g' in the plate a' and 85 into the compartment formed between the upper and lower plates a , a' . A pin is secured to the plate a' and is adapted to be turned across each clamp as shown in Fig. 3 to hold said clamps in the position shown in 90 Fig. 3.

When the device is to be used, the extension arms are pulled from each side of the casing to a position in line with the casing body as shown in Figs. 1 and 2. The arms 95 A and A' are held quite rigidly in position by being pressed into the grooves by the springs c .

It will be observed that I have provided a hanger which is very simple in construction, can be folded into a very small space and one which is quickly and readily adjusted for use.

I claim:

A clothes-hanger, comprising an elongated 105 casing formed of an upper and a lower plate, disks interposed between the ends of said plate to form a compartment therebetween, extension arms pivotally secured at the ends of said casing and adapted to 110

fold inside of the same, each of said plates having a groove formed in one end thereof on its inner surface, springs between the ends of said plates exerting a pressure against the pivotal ends of the extension arms whereby they are held in the grooves when in open position, substantially as described.

In testimony whereof I have signed this specification in the presence of two subscribing witnesses.

GRACE FERN PETER.
